[57] **ABSTRACT**

A wading pool, sandbox or like thermoformed structure is provided with an integral slide, hollow hand rail, and ladder step molded into the structure. The structure is configured to provide the slide and a slide mounting platform, disposed above the top of the side walls of the structure, with sufficient strength and rigidity in combination to require only a single, simplified, inverted U-shaped, tubular support under the slide mounting platform adjacent and within the hollow peripheral edge of the structure, to stabilize and to support the slide mounting platform. With such an arrangement, assembly is simplified and the container may be easily folded after assembly for transport without dismantling.

FIG. 1

FIG. 2

FIG. 3

FIG. 4

THERMOFORMED WADING POOL WITH INTEGRAL SLIDE AND HAND RAIL

BACKGROUND OF THE INVENTION

As is well known, many vacuum formed or otherwise molded thermoplastic wading pools, sandboxes, and the like have been proposed as play areas for small children. Moreover, such structures have been proposed incorporating integral central or side slides and/or seats which enhance the attractiveness and play value of the structures. Separate ladder steps and hand rails are typically provided for the central slide pools. In addition, integral mounting platforms for the slides have been proposed which are well above the top edge of the peripheral walls of the container providing a longer and higher slide and greater play value than slides which extend from or below the peripheral flanges of the container.

SUMMARY PRESENT INVENTION THE INVENTION

In accordance with the present invention, a wading pool or sandbox is provided with an integral central slide and with an integral elevated mounting platform therefor disposed well above the top edges of the peripheral wall of the container, which slide has integral hand rails and an integral ladder step. The new structure is comprised of a single sheet of a thermoplastic material which may be vacuum formed into the final configuration of the structure. The structure is so configured with integrally formed supporting ribs, ladder step, and hand rails in a manner whereby only a single, symmetrical U-shaped tubular support member is required and assembly is simplified. This support is disposed adjacent the peripheral edge of the pool in a manner in which no portion of the tubular support extends inwardly of the container. Thus, the pool may be readily folded for transport, as desired, after assembly of the support.

The new pool structures, in accordance herewith, are vacuum formed from thermoplastic sheet material under heat and pressure by known techniques. The thermoplastic sheet material may be, for example, polyethylene, polypropylene, or copolymers thereof with other olefin monomers or the like.

Accordingly, with the foregoing and other objects in view, this invention will now be more particularly described, and other objects and advantages hereof will be apparent from the following description taken in conjunction with the accompanying drawings.

DESCRIPTION OF THE DRAWINGS

FIG. 1 is a perspective view of a wading pool embodying the invention;

FIG. 2 is a top plan view of the wading pool of FIG. 1;

FIG. 3 is a side elevational view of the wading pool of FIG. 1; and

FIG. 4 is a fragmentary, cross-sectional view of the wading pool of FIG. 2 taken along lines 4-4 thereof.

DETAILED DESCRIPTION OF A PREFERRED EMBODIMENT OF THE INVENTION

Referring now to the drawings, like reference numerals refer to like elements throughout the several views thereof. As indicated in FIG. 1, the new wading pool 10 is comprised of a bottom wall 11 surrounded by a circu-

lar upstanding wall 12. (Although the wading pool is shown as circular in form, it will be understood that it is within the purview of this invention that the pool may be rectangular, oblong, square, etc.) A flange 14, having an arcuate cross section, is provided along the upper edges of the wall 12, while the bottom wall 11 is embossed with ridges 13 to provide a non-skid surface. As is conventional with such pools, the side walls 12 have incorporated therein molded-in ribs 16 or the like for providing enhanced rigidity to the walls.

As illustrated in FIG. 1, an integral central slide, generally designated 20, is formed as part of the container, and it includes a slide mounting platform 22 elevated substantially above the peripheral flange 14 circum-

scribing the pool. An inclined slide surface 24 extends from platform 22 to the bottom wall 11 of the container (FIGS. 1 and 2). The slide has wide ribs formed in tapered side walls 26 and 28. The ribs 27 of side walls 26 and 28 of slide 20 provide enhanced rigidity for the slide.

Integral web-like, triangular seats 34 and 36, extend in a horizontal plane between the slide side walls 26, 28 and the outer pool wall 12. Seat walls 12a extend from the bottom wall 11 to the front edges of the seats, as shown.

In accordance with the invention as shown in FIGS. 1 and 3, integral hand rails 30, 32 project upwardly from side walls 26, 28, to provide hand grips for the user in the vicinity of the platform 22. Extending between these hand rails 30 and 32 are integrally formed generally inverted U-shaped supporting ribs 52, 53, which provide lateral support extending from each side wall 26, 28 and generally define the edges of the mounting platform 22. Side rails 56, 58 of inverted U-shaped cross section extend from hand rails 30, 32 and border the side edges of the slide surface 24.

As best shown in FIG. 3, a recess 37 is formed integrally with an enlarged skirt portion 14a of flange 14 adjacent the slide area, to provide an integral horizontal foothold 38 or ladder step for ascending the slide mounting platform 22. Moreover, the recess 37 provides further rigidity to the pool structure.

As an important aspect of the invention and as shown in FIGS. 3 and 4, a single, inverted U-shaped support 46, which may be formed, for example, from aluminum tubing or injection molded plastic, is sufficient to reinforce and to support the integral central slide. The supporting structure 46 is comprised of vertical legs 42, 44 interconnected by an upper horizontal crossbar portion 40 extending beneath the platform 22. The legs 42, 44 are generally converging to conform with and to bear against the outermost slide side wall portions 26a, 28a (FIG. 2). This enhances further the rigidity of the entire structure. More specifically as shown in FIG. 4, the crossbar 40 is nestingly disposed in the outermost supporting rib 52 of platform 22. None of the supporting structure extends into the container body itself to interfere with folding of the container. The crossbar 40 has a single, centrally disposed hole for receiving a bolt and nut 48 for assembling the supporting structure 46 to the container structure. Similarly, each of the legs 42, 44 has a hole for receiving bolts and nuts 50 for securing the lowermost portions of the skirt 14a to the support. It will be apparent, however, that the connecting bolts may be arranged differently and more may be used if desired or other fasteners, e.g., self-tapping screws, may be used in lieu of nuts and bolts.

Thus, as should be apparent from the foregoing, there is provided in accordance herewith an improved thermoformed play structure or container for use as a wading pool, sandbox, or the like, having an integral central slide with molded in hand rails. Most importantly, the new structure reduces external support for the slide structure to a single, simple support which may be simply and quickly assembled with the pool. Only a few fasteners are required to attach the support.

The new structure enables a substantial reduction in the costs of thermoformed central slide pools to be realized. It should be emphasized, further, that with only a single, simple support, without separate steps or the like, an entire integrated structure is provided with a built-in slide, built-in hand rails and a built-in ladder step. Since the entire new pool structure is formed from a single sheet of thermoplastic material and a single support brace, the new structure is particularly adapted for mass production techniques. Thus, the new and improved pool structure compares most favorably from cost, use, and functional aspects with known thermoformed central slide pools.

While the arrangements of the new structure herein described constitute preferred embodiments of this invention, it is to be understood that the invention is not limited to these precise arrangements of structure, and that changes may be made therein without departing from the scope of the invention which is defined in the appended claims.

We claim:

1. In a container structure comprised of a single thermoformed sheet of plastic material having a flat bottom wall of predetermined configuration and circumscribing peripheral side walls of a predetermined height ex-

tending upwardly therefrom; a flange at the upper edge of said side walls; and an integral sliding surface sloping upwardly from said bottom wall to a mounting platform therefor spaced well above the said predetermined height of said side walls; the improvement comprising

- 5 a. side walls for said slide structure extending from said flat bottom wall to said mounting platform, said side walls being rigidified by heavy vertical ribs;
  - b. a hollow hand rail on each side of said mounting platform, each of said hand rails including portions integral with said slide side walls and forming upwardly extending extensions thereof;
  - c. a pair of generally integral horizontal ribs extending along the inner and outer edges of said mounting platform between said hand rails;
  - d. said flange including an enlarged skirt portion extending between said hand rails;
  - e. an inverted U-shaped support fastened to inner surfaces of said skirt portion.
2. The container structure of claim 1, in which
    - a. said support is a single, generally U-shaped aluminum tube including a generally horizontal crossbar extending between a pair of converging legs.
  3. The container structure of claim 2, in which
    - a. said crossbar is nestingly disposed in the outer horizontal supporting rib; and
    - b. each of said legs and said crossbar of said support is fastened to said skirt portion by mechanical fastening means.
  4. The container structure of claim 1, in which
    - a. a recess is formed in said skirt portion to establish a foothold.
